UNITED STATES PATENT OFFICE.

JEFFERSON G. WRIGHT, OF CONNELL, WASHINGTON, ASSIGNOR OF ONE-THIRD TO
WILLIAM F. STEINMEIER, OF ELTOPIA, WASHINGTON.

WASHER.

1,344,194.

Specification of Letters Patent. Patented June 22, 1920.

Application filed August 4, 1919. Serial No. 315,214.

To all whom it may concern:

Be it known that I, JEFFERSON G. WRIGHT, a citizen of the United States, residing at Connell, in the county of Franklin and State 5 of Washington, have invented certain new and useful Improvements in Washers, of which the following is a specification, reference being had to the accompanying drawings.

10 This invention relates to washers such as are used on axles in harvesters, and in fact in all kinds of machinery, and the general object of this invention is the provision of a sectional washer which may be easily re- 15 moved from the part to which it is applied or as easily applied without the necessity of removing from the shaft, rod, axle, or other part, elements which may be mounted thereon, which is necessary where the ordinary 20 one-piece, annular washer is used.

My invention is illustrated in the accompanying drawings, wherein:—

Figure 1 is a top plan view of a washer constructed in accordance with my invention;

Fig. 2 is a top plan view of the washer with its parts expanded;

Fig. 3 is an edge elevation of the washer closed;

30 Fig. 4 is a section on the line 4—4 of Fig. 1.

Referring to these figures, it will be seen that my improved washer consists of two parts A and B, each part or section being 35 approximately semi-circular in form. The adjacent ends of the two sections are reduced in thickness, as at 10, so that the reduced end of the section B will fit against the reduced end of the section A, and these ends 40 are pivotally connected to each other by means of the rivet 11 so that the two sections may be opened out to the position shown in Fig. 2, are closed to the position shown in Fig. 1. Each section A and B at

45 its end remote from the rivet 11 is reduced in thickness, as at 12, and notched on its exterior margin, as at 13. This leaves a relatively thin terminal 14 on each section which is adapted to overlap the corresponding terminal 14 on the other section when the two sections are closed together. The 50 extremities of each of these relatively thin terminal portions 14 are off-set or slightly bent, as at 15. Now these terminal portions 55 15 and the relatively thin terminals 14 are

slightly resilient or yielding, so that when the two sections are brought together in the manner illustrated in Fig. 1, these off-set or bent tongues 15, as they may be termed, will be depressed into the notches or recesses 13 in the manner shown in Fig. 3, thus yieldingly holding the free ends of the two sections in engagement with each other to form a circular washer. When the free ends of the two sections are brought together, these terminals 14 will abut against the shoulders 16 formed by reducing the thickness of the sections to form the terminals 14, thus limiting the inward movement of the two sections with relation to each other.

I do not wish to be limited to the particular construction of this washer, except as stated in the appended claims, and I have found in actual practice that washers of this character will stand the same amount of pressure as an ordinary washer and that these washers will run smoothly and without any increased friction over the ordinary washer. Furthermore, I find in practice 80 that when these washers are put in place, they will hold and their free ends will not become detached from each other. Experience has shown that these washers have to wear extremely thin before falling or coming off. It is also pointed out that while these washers will be held in place by reason of the engagement of the deflected ends 15 of the terminals 14 with the notches 13, yet the washers may be removed at any time by 90 simply pulling the sections A and B apart, causing the deflected terminals 15 to ride over the terminals 12. I have found that they are particularly convenient, readily put in place, and readily removed if desired, 95 which as before remarked, is not the case with the ordinary washer.

I claim:—

1. A washer formed of two semi-circular sections, each section at one end being reduced in thickness to thereby permit these ends of the sections to overlap each other, said overlapping portions being pivoted to each other whereby both sections are disposed and move in the same plane, the free 100 ends of the sections being reduced in thickness to overlap each other, and means on the last named overlapping portions of the sections disposed and operating entirely within the facial planes of the washer, resiliently 105 110

- holding the free ends of the sections in engagement with each other but permitting the free ends of the sections to be drawn apart upon the application of force thereto.
- 5 2. A washer formed of two semi-circular sections, each section at one end being reduced in thickness to thereby permit these ends of the sections to overlap each other, said overlapping portions being pivoted to
- 10 each other whereby both sections are disposed in the same plane to thereby permit the free ends to overlap each other, the outer periphery of one of said sections at the inner end of said reduced portion being notched
- 15 and the extremity of the free end of the other section being formed with a deflected tongue yieldably engaging in said notch.
3. A washer formed of two semi-circular sections, each section at one end being reduced in thickness to thereby permit these ends of the sections to overlap each other, said overlapping portions being pivoted to each other whereby both of said sections are disposed and move in the same plane, the
- 20 free ends of the sections being reduced in thickness to thereby permit the free ends to overlap each other and to form shoulders
- 25

limiting the overlapping or closing movement of the sections, and means on the last named overlapping portions of the sections 30 and disposed and operating within the facial planes of the washer, resiliently holding the free ends of the sections in engagement with each other but permitting the free ends of the sections to be drawn apart 35 upon the application of force thereto.

4. A washer formed of two semi-circular sections, each section at one end being reduced in thickness to thereby permit these ends of the sections to overlap each other, 40 the overlapping portions being pivoted to each other, the free ends of the sections being reduced in thickness to thereby permit the free ends to overlap each other, the reduced, free end portion of one section being 45 formed with an aperture, the extremity of the free end of the other section being formed with a resilient, deflected tongue yieldably engaging in said aperture to thereby detachably hold the sections in engagement with each other.

In testimony whereof I hereunto affix my signature.

JEFF WRIGHT.
